UNITED STATES PATENT OFFICE.

EDMUND L. KENOYER, OF SELMA, CALIFORNIA.

BROOM.

1,191,975.

Specification of Letters Patent. Patented July 25, 1916.

Application filed December 13, 1915. Serial No. 66,537.

To all whom it may concern:

Be it known that I, EDMUND L. KENOYER, citizen of the United States, residing at Selma, in the county of Fresno and 5 State of California, have invented new and useful Improvements in Brooms, of which the following is a specification.

This invention relates to brooms, and its object is to provide a novel and improved 10 means for securing the broom brush to the handle so that the brush may be removed when worn out and replaced by a new one.

With the object stated in view, the invention consists in the combination and arrangement of parts to be hereinafter described and claimed, and in order that the same may be better understood, reference may be had to the accompanying drawing forming a part of this specification.

20 In the drawing—Figure 1 is an elevation of the invention; Fig. 2 is an elevation with one of the attaching plates removed; Fig. 3 is an enlarged section on the line 3—3 of Fig. 1; Fig. 4 is a section on the line 4—4 of Fig. 2; and Fig. 5 is a section on the line 5—5 of Fig. 1.

Referring specifically to the drawing, 5 Fig. 5 denotes a broom brush sewed together in the ordinary manner. Around the brush, near 30 the top thereof, is secured by rivets or other suitable fastening means, a plate 6 having, on opposite sides of the brush, an outstanding flange 7, which is for a purpose to be presently described.

35 The brush 5 is secured to the broom handle 8 by a holder composed of two opposite plates 9 reduced in width at their upper ends and shaped here to encircle the lower end of the broom handle. The two 40 plates are secured to the broom handle by bolts 10, and they are crimped at their edges to overlap and to cover the edges of the brush, so that the upper portion of the latter is entirely inclosed. In the sides of the 45 plates are transverse grooves or depressions

11, the same being on the inside and positioned so that the flanges 7 may seat therein, whereby the brush is securely held between the plates and prevented from slipping out of the same. The bottom edges 50 of the plates are fastened together by tongues 12 on one plate passing through slits 13 in the other plate and bent back into a hook.

The brush 5 is readily applied, and when 55 worn it can be removed and replaced by a new one. The brush is applied by loosening the bolts 10 and disengaging the tongues 12. The plates are then spread and the brush is inserted from the bottom of the 60 same, and upon tightening up the bolts 10 and inserting the tongues 12 through the apertures 13, the brush is securely held in place on the handle 8.

The structure hereinbefore described provides a simple and cheap broom, and one 65 which enables the brush to be readily renewed when worn. The brush, with the exception of the flanged plate 6, is made in the ordinary way, (except the tying) and no 70 specially constructed brush is required. A broom, as ordinarily constructed, becomes worthless after the brush is worn away, and the entire broom must be discarded. This 75 waste of the broom handle is entirely obviated by the present invention, and the handle can be used over and over again.

The invention is applicable to all kinds of brooms, as well as to brushes.

I claim:

The combination of a brush, a handle, opposite plates secured to the handle, between which plates the brush is held, said plates having transverse grooves on the inside, and plates on opposite sides of the brush, said 85 plates having outstanding flanges seating in the grooves.

In testimony whereof I affix my signature.

EDMUND L. KENOYER.
